UNITED STATES PATENT OFFICE.

HARRY WILLIAM GAULD, OF BRANDON, MANITOBA, CANADA.

STARTER FOR GAS ENGINES.

Application filed October 13, 1921. Serial No. 507,521.

To all whom it may concern:

Be it known that I, HARRY WILLIAM GAULD, a citizen of Canada, residing at Brandon, in the Province of Manitoba, 5 Canada, have invented certain new and useful Improvements in Starters for Gas Engines, of which the following is a specification.

My invention is in relation to gas engines and the object thereof is to supply 10 a simple and efficient mechanism comprising a quietly engaging and nonwheel damaging starter and engine cooperation eliminating the heavy expense of new fly-wheels and the aftermath, if they happen to be 15 installed by incompetent or careless workmen, because a vast majority of gas engine fly-wheels in use have a goodly portion of the teeth worn away opposite the starter 20 pinion where they habitually stop because of engine compression and consequently where they most often receive the impact and twist of the pinion and where they finally will disappear.

Using general terms, my starter comprises 25 a motor of any kind, as for instance, an electric motor able to operate a rotatable, threaded driving member, either its armature shaft extended and adapted, or another driven by it and adapted to cooperate 30 with the teeth on the periphery or some smaller diameter of the fly-wheel or some other wheel driven by the engine, the said driving member being arranged to be manually advanced into cooperative position with 35 the engine wheel and automatically expelled therefrom when the engine starts. In connection with this construction I use a push and pull button ended rod on the instrument board, in the case of an automobile, 40 for the manual engagement of the driving member, the opposite motion of this rod to retard the spark and operate the switch of the starting motor and incidentally doing 45 away with the floor button.

In the drawings, Figure 1 is a sectional elevation of a starting motor showing one 50 of the ways of installing a jointed base capable of allowing the rocking motion to the driving member necessary to the device.

Figure 2 is a sectional elevation of part of my invention showing the formation of the driving member and of the member to be driven in the operation of starting the

engine, but a section of the latter being 55 employed.

Figure 3 is a sectional elevation of parts, some of which are not new, that I make no claims for, and for that reason and for the sake of clearness have here disassociated them from the rest. 60

The first two figures are looking from the fly-wheel forward, the third is looking crosswise of the engine from the left side to the right. Similar reference characters refer to similar parts in the different figures. 65

Describing the construction shown in the drawings, in Figure 1 the starting motor is presented mounted on the rocking base 70 (14), on the fly-wheel housing (10), enabling it to have the rocking motion necessary to the device.

In Figure 2, the engine wheel (3), which is here intended either as the fly-wheel or 75 a wheel on the same axis and in the same plane and in operative connection with it, is provided on its periphery with semi-conical shaped teeth, the backward side of which engaging the fore-side of the engaging 80 members (1) threads and the forward side engaging the backward side of the engaging member (1) threads, the former taking place when the starter starts the engine and the latter taking place when the engine starts under its own power and expels 85 the starting member threads. The end and side thrust is taken care of by the bearing (9), which moves up and down with the driving member it is upon in the slide (5) 90 which is provided with side and end thrust surfaces made in the casting (6) upon the fly-wheel housing (10).

The balls, race, and cone of thrust bearing (9) are shown by dotted lines. The 95 casting (6) is chambered and contains the inner exposed end of a spring pressed bolt (11), the lower end of a vertically sliding plunger (2) and a pin like extension of the member (1), the extension being in the path 100 of the plunger and having a cone shaped end, which in the swinging movement of the member (1) engages with the coned end of the bolt. A set screw is provided for adjusting the pressure of the spring. 105

According to the above arrangement it will be seen that the driving member 1 is maintained both in and out of engagement

with the member 3 by the bolt and that the weight of the motor by virtue of its offset pivoting acts to augment the up-swinging of the member (1) when the same is forcibly expelled by the teeth of the driving member 3.

In Figure 3 is shown not the construction of my invention, but the connection between the driving compartment and the invention, 10 and the connection between the invention and the spark distributor which is all handled in the description of operation, and to go further here would be a repetition.

Describing the operation of my starter 15 and assuming that shaft (1) Fig. 2 is in disengaged position, the first step by the driver is the engaging of it, which is done by pulling button ended rod (12), situated in a convenient place in the driving compartment, thereby depressing control rod (7) by means of bell crank (13) consequently plunger (2), into which rod (7) is screwed causing the drive shaft (1) to take the position shown in the drawing, if not immediately, then upon a small fraction of a turn of the shaft, and as far as the actual engaging is concerned, without sound.

This done, the driving compartment button is pushed back as far as it will go, it 30 then has removed plunger (2) from the path of the engaging member (1), plunger (2) has retarded the spark by means of the end of the cut away portion in it together with the bell crank (8) and by means of bell crank (8) has later operated starter button and switch (4). Starting having taken place, it then freed the bell crank (8) and the retarded spark ready for advancement, because of the back pressure from the switch 40 spring. The driving compartment button is then a little way out and into home position.

The above covers the explanation of operation except as to the dual connection of 45 steering wheel quadrant and distributor, which follows: The distributor is self advancing and its control rod divided, that part attached to itself terminating in the saucer-like disc (15). The spark control 50 rod (16) from the quadrant butting it, likewise that from the starter control.

I claim:

1. In a gas engine starter, the combination 55 with a toothed driven member associated with the engine, of a toothed driving member engageable with the teeth of the

driven member, a motor driving the drive member, the said motor being pivoted to permit of the swinging of the drive member towards and away from the driven member, the teeth of said members being designed to swing the drive member away from and out of engagement with the driven member upon the driven member becoming a drive member, means for manually engaging the said members, and means for releasably locking the members in and out of engagement.

2. In a gas engine starter, the combination with the engine fly wheel, said fly wheel having peripheral teeth and the fly wheel housing, of a driving motor pivotally mounted on the housing, a driving shaft extending from the motor and operated thereby, said shaft being provided with driving teeth 75 in the form of a worm, the said worm being engageable with the teeth of the fly wheel and the said teeth of the worm and the fly wheel being arranged such that they remain engaged to effect the driving of the fly wheel by the motor and force themselves out of engagement upon the fly wheel becoming the driving member under the action of the engine, and means for manually engaging the worm initially with the fly wheel. 80

3. In a gas engine starter, the combination with a peripherally toothed driven member, of a pivotally mounted motor having an extending driving shaft positioned tangentially of the toothed driven member and 90 fitted with a worm engageable with the latter, the teeth of the worm and the driven member being designed such that they hold themselves into engagement when the motor is driving the driven member and force 95 themselves out of engagement upon the driven member becoming a driving member.

4. In a gas engine starter, the combination with a peripherally toothed driven member, of a pivotally mounted motor having an extending driving shaft positioned tangentially of the toothed driven member and fitted with a worm engageable with the latter, the teeth of the worm and the driven member being designed such that they hold 100 themselves in engagement when the motor is driving the driven member and force themselves out of engagement upon the driven member becoming a driving member, and means for initially engaging the worm 110 with the driven member.

HARRY WILLIAM GAULD.
